CLAIM

The ornamental design for a combined toilet seat and locking cover, as shown and described.

DESCRIPTION

FIG. 1 is a perspective view of the combined toilet seat and locking cover showing our new design.

FIG. 2 is a front elevational view thereof.

FIG. 3 is a rear elevational view thereof.

FIG. 4 is a side elevational view thereof, the side opposite being a mirror image of the side shown in FIG. 4.

FIG. 5 is a top plan view thereof.

FIG. 6 is a bottom plan view thereof.
